ELECTRIC REGULATOR

Frederick Newton, Derby, England, assignor to
 Newton Brothers (Derby) Limited, Derby,
 England

Application December 17, 1941, Serial No. 423,387
 In Great Britain January 14, 1941

12 Claims. (Cl. 201—51)

This invention relates to electric regulators and more particularly has reference to regulators having carbon pile or other electric controlling elements actuated by the differential effect of opposed electromagnetic and spring forces.

In an electromagnet system the total contained energy is proportional to the product of the magnetic flux and the magneto motive force (i. e. the product of the flux and ampere turns).

Neglecting leakage, fringing, and the ampere turns required by the iron in the magnetic circuit and/or assuming that for a given value of excitation the flux present in a system is inversely proportional to the length of the magnetic air path, the force of the attraction of the armature to the poles will vary inversely as the square of the magnetic air path and where the air path is contained entirely between the armature and the poles, the attractive force will vary inversely as the square of the distance of the armature from the poles.

For various applications such as sensitive relays, carbon pile regulators and the like it is desirable to provide for the magnetic attractive force an equal and opposing force free from hysteresis, so as to establish for a given degree of excitation a condition of differential equilibrium where small increases or deductions of excitation make available substantially large forces, through a desired distance in a positive or negative sense from the datum value as may be required for operational purposes.

Further it is very desirable that such a system should have the qualities of a high natural period of mechanical vibration, that is to say, the equilibrium forces should be great compared with the weight of the moving parts, and that the system should be aperiodic, so as not to require a dash pot or other damping means and so as not to be resonant to any periodic influence.

An object of this invention is to provide an electric control apparatus having an electric modifying device actuated by the differential effect of the opposing actions of an electromagnet and a spring.

Another object of this invention is to provide a spring for opposing a variable magnetic force.

A further object of this invention is to provide an electric control apparatus having an electric modifying device actuated by the differential effect of the opposing action of an electromagnet and a spring, said spring including at least two resilient leaves tangentially engaging and wrapping upon each other as they are stressed.

Still another object of this invention is to pro-

vide a spring for opposing an electromagnetic force and comprising at least two curved resilient leaf-like elements tangentially engaging each other and connected at one end whereby flexure of the free ends toward each other will cause one element to wrap upon the other.

In the drawings:

Fig. 1 is a vertical sectional view of a control device constructed in accordance with the present invention.

Fig. 2 is a plan view of the device shown in Fig. 1.

Fig. 3 is a somewhat diagrammatic illustration of a spring embodying the features of the present invention.

Fig. 4 is another diagrammatic view illustrating a modified form of spring.

Fig. 5 is still another diagrammatic view illustrating a cantilever type of spring.

Fig. 6 is another diagrammatic view illustrating a modified form of cantilever spring.

Fig. 7 is a diagrammatic view illustrating a spring of unitary construction.

Fig. 8 is a view similar to that of Fig. 3 illustrating still another modified form of spring.

Fig. 9 is another diagrammatic view illustrating still another modified form of spring in which the ends of the two components are secured together.

Fig. 10 is a view similar to that of Fig. 3 illustrating a spring in which the components are formed of a plurality of layers which may be bimetallic.

Referring to the drawings, there is shown in Figs. 1 and 2 a carbon pile controller constructed according to the present invention.

As illustrated, an electromagnet is provided having a fixed core 1 surrounded by a magnet winding 2. A lower lateral extension 3 is secured to the core 1 by means of a screw 4 which extends through an opening in the lower end of core 1 and is received in a threaded bore of the extension 3. The end 5 of screw 4 projects through the threaded bore in extension 3 and has the thread cut away and slightly rounded as shown for a purpose to be hereinafter described.

At the upper end of core 1 an upper lateral extension 6 is mounted and secured in place by a screw 7 extending through an opening in the core 1 and entwined in the threaded bore 8 of the extension 6. The above construction provides a U-shaped core excited by the winding 2.

Cooperating with the U-shaped core formed of the core 1 and extensions 3 and 6 is an armature

8. A winding 10 is carried by the armature intermediate its ends.

If desired, winding 10 may be rigidly supported in which case the armature will be loosely mounted therein for free movement.

At its lower end armature 8 is provided with a recess 11 to receive the rounded end 5 of screw 4. This connection serves merely to position the lower end of the armature 8 relative to the lower extension 3 of the U-shaped core upon which the armature abuts and pivots, the lower end face of extension 3 serving as a fulcrum about which armature 8 pivots.

An opening is formed in the upper end of armature 8 in alignment with the bore 8, and a screw 12 passes loosely through said opening and is entwined into the threaded bore 8 as shown.

Part of the bore in the upper end of armature 8 is enlarged to receive the sleeve 13 of insulating material which serves as a mandrel for the carbon discs 14 of the carbon pile.

On the outer end of screw 12 adjacent the head thereof is mounted a metal disc 15 which conductively engages the outermost carbon disc of the pile. A second metal disc 16 is mounted on the insulated sleeve in conductive engagement with innermost carbon disc of the pile. Disc 16 abuts on insulating disc 17 which engages the armature 8. The discs 15 and 16 serve as the terminals of the carbon pile.

With the construction described it will be realized that upon energizing the windings 2 and 10 of the electromagnet the armature will be attracted to the pole pieces which are in effect the free end faces of the lateral extensions 3 and 6. Movement of the armature 8 especially the upper portion thereof toward the magnet will permit the terminal disc 16 to be moved relatively to the terminal disc 15 to decrease pressure on the carbon pile 14.

In accordance with the present invention pressure is exerted on the carbon pile by means of a spring the resistance to flexure of which increases as it is flexed by the electromagnet tending to separate the carbon pile and proportional to the attractive force of the electromagnet exerted on the armature. As illustrated, a support block 18 is mounted on the upper surface of extension 6 by means of screws 19. Block 18 has a threaded bore extending therethrough parallel to the bore 8 and has a screw 20 threaded therein.

A stop block 21 is mounted on the upper end of armature 8 by means of screws 22.

As shown in the drawings, a spring 23 is positioned between the block 21 and the end of screw 20 which tends to move the block 21 away from the end of screw 20.

Spring 23 is of special construction which is one of the features of the present invention and in this connection attention is directed to Fig. 3 of the drawings which diagrammatically shows a spring similar to spring 23. In Fig. 3, however, two beam spring components 24 and 25 of V-shaped formation are shown with the ends of one component in engagement with those of the other component and the apices of the two components remote from each other. Now when the spring components 24 and 25 are stressed relatively displacing the apices 26 and 27 toward each other to the position shown in full lines in Fig. 3, the portions of the arms of one component inwardly from the ends thereof are successively forced into contact with the corresponding portions of the arms of the other compo-

5 nent. In other words, portions of one spring component are wrapped upon corresponding portions of the other spring component.

Thus one spring component serves as an abutment upon which the other spring component wraps in a manner similar to that described in my copending application, Serial No. 299,326, filed October 13, 1939.

10 As the apices 26 and 27 are pressed together and as the regions of contact between the spring components 24 and 25 extend inwardly between the extremities of the components, the free length of the components between the regions of contact decreases which increases the resistance of the spring components to further flexure. I have found that a spring constructed as described relative to Fig. 3 resists flexure with a force inversely proportional to the square of the flexing displacement. Such a spring is ideal for use in opposing and balancing a force exerted by an electromagnet.

15 The spring 23 shown in Figs. 1 and 2 comprises a component 28 having its mid portion in engagement with block 21 and a component 29 having its mid portion in engagement with the end of screw 20. It will be noted that the two components 28 and 29 are joined at one end as indicated by reference character 30 and that the free end of component 28 is formed as an extension 31 which is bent back upon itself to provide a supporting arm 32.

An opening is formed in the end of arm 32 by means of which said arm is mounted on screw 20.

20 A lock nut 33 is threaded on screw 20 and serves to secure the arm 32 tightly against block 18 which maintains the spring 23 in proper position between the stop block 21 and the end of screw 20. Lock nut 33 also serves to lock screw 23 in adjusted positions to which it may be moved to vary the initial stress on spring 23.

25 The parts of the device of Figs. 1 and 2 are assembled as illustrated and screw 20 is adjusted to place spring 23 under the desired stress and screw 12 is adjusted to cooperate with the spring to subject the discs of carbon pile 14 to the pressure necessary to provide for the desired flow of current. With the windings 2 and 10 of the electromagnet subject to the electric current or potential to be regulated as the current or potential increases the electromagnetic force opposing spring 23 increases to reduce the pressure on carbon pile 14 and thereby increase its resistance which serves to effect a reduction of the current or potential to which the electromagnet windings are subjected. This action produces the regulation desired. Now to maintain equilibrium between the magnetic force and the opposing spring force the latter must increase proportionally to the magnetic force. The spring 23 is constructed to increase its resistance to flexure, as it is stressed, in a manner corresponding to the increase in magnetic force, and for each variation in the magnetic force exerted on the armature there is a corresponding variation in spring resistance so that although there is a slight displacement of the armature and its associated carbon pile, the armature is always in a stable position wherein equilibrium between the opposing magnetic and spring forces exerted thereon exists.

30 The core 1 and extension 3 are mounted upon a base 71 by means of screws 72 which extend through bushings 73 of insulating material to insulate the base from the screws. A plate 74

of insulating material serves to insulate the core from the base 71.

A terminal box 75 is mounted on the base. As shown, the side portions of the base are turned up to provide flanges 76 to which screw sockets 77 are attached for securing a housing 78 to the base.

In Figs. 1 and 2 a spring structure is shown which operates successfully in this installation but a number of other forms of springs may be used. For instance, a spring as shown in Fig. 3 may be satisfactorily used if some means of retaining the components in associated relation is provided.

A spring of the type shown in Fig. 7 may be used. This spring is of unitary construction in that the two components 34 and 35 are integral. When the apices 36 and 37 of this spring are urged toward one another, the portions of the two components from the joined ends 38 and 39 towards the apices are progressively brought into contact with each other to cause portions of one component to progressively wrap upon corresponding portions of the other component in the manner described in connection with Figs. 1-3 even though the two components are integral.

In Fig. 9 a spring is shown formed of two separate components 40 and 41 which are joined at their ends by rivets 42. This spring functions in the same manner as the springs previously described.

Those springs in which the two components are integral or joined are initially stressed in manufacture and can be more easily installed in an apparatus in which they are to be used than the unstressed springs.

In the preceding figures the springs have been shown as formed of unitary constructions or embodying two separate or attached components. It is conceivable however, as illustrated in Fig. 4, to construct a spring embodying the principles of the present invention wherein each component is formed of a pair of separate arms secured in place in a rigid body. As illustrated in Fig. 4, the spring comprises a rigid body 43 having two arms 44 and 45 formed of spring material embedded therein. The rigid body 43 and the two arms 44 and 45 form one component of the spring structure. Associated with the aforesaid component is a second component formed of a rigid body 46 and arms 47 and 48 formed of spring material and embedded in the rigid body 46.

When the spring device of Fig. 4 is in an unstressed condition the arms of the several components will appear as illustrated in dotted lines in Fig. 4 and when the spring is under stress the spring arms will assume the position shown in full lines. The function of the spring of Fig. 4 is practically identical to that of the spring illustrated in Fig. 3 and the other figures.

The springs described hereinbefore are all of what may be termed the beam type in that each component is in the form of a beam having two angularly positioned arms of V-shaped formation as shown in Fig. 3 or of the formation shown in Fig. 4. It is within the concept of the present invention, however, to utilize cantilever types of springs. In this connection there is shown in Fig. 5 of the drawings a spring in which each component comprises a rigid element having a single resilient arm embedded therein. As illustrated, one component of the spring comprises a rigid body 49 having a resilient arm 50 embedded therein and the other component comprises a rigid body 51 having a resilient arm 52 embedded

therein. In the cantilever type of spring it is necessary to restrain the movement of the rigid bodies 49 and 51 so that they will move in a fixed path relative to each other. The contacting free ends of the resilient elements 50 and 52 as indicated by reference character 53 are free to move laterally as in the case of the preceding figures. When the spring components are in an unstressed condition they assume the position shown in dotted lines in Fig. 5 and when in a stressed condition the portions of the spring elements 50 and 52 adjacent the ends 53 thereof progressively wrap upon each other in the same manner as described in connection with Fig. 3 to progressively shorten the effective lengths of the arms 50 and 52 as the rigid bodies approach each other. This spring construction functions in substantially the same manner and has substantially the same characteristics as the springs of the so-called beam type hereinbefore described.

In Fig. 6 there is illustrated a modified form of cantilever spring in which the two components 54 and 55 are integral or joined at their ends 56. The arms or components 54 and 55 of the spring shown in Fig. 6 are initially curved as distinguished from a true V-shape so that when the free ends 57 of the component 54 and 58 of the component 55 are moved toward each other, the portions of the spring adjacent ends 56 will progressively wrap upon each other as described in connection with the preceding figures.

The springs of Figs. 3, 7 and 9 have been described as having components of V-shaped formation. It is not necessary that the components be of V-shaped formation but it is only necessary that the arms thereof be angularly arranged as for instance, is the case of the structure shown in Fig. 4 or the components may be of substantially U-shaped formation. In the latter case it is better that the components be of an open U-shaped formation in which the arms of the U are initially flared outwardly. In Fig. 8 of the drawings there is shown a spring construction in which the components 59 and 60 are of open U-shaped formation. When a spring of this type is placed under stress with the ends of one component in engagement with the other as indicated by reference characters 61 and 62 and the spring is stressed by causing the mid point 63 of component 59 to approach the mid point 64 of component 60, the end portions of one component are wrapped upon the end portions of the other component as an abutment as described in connection with the preceding figures.

As is well known, temperature variations affect the functioning of shunt wound magnet windings and in order to compensate for such temperature variations the present invention includes the structure shown in Fig. 10. In this figure the spring is formed of two components 65 and 66, the component 65 being formed of two layers 67 and 68 and the component 66 being formed of two layers 69 and 70. The two layers of the components are of different metals or rather of metals having different coefficients of expansion so that the arms of the two components are in effect of bi-metal construction. The two metals forming the arms of the components are selected to produce the desired deformation under temperature variations to compensate for the effect of temperature variations upon the magnet windings. The spring construction shown in Fig. 10 apart from the bi-metallic structure operates in substantially the same manner as the structure shown in Fig. 3.

In some instances it may be desirable to construct springs of a plurality of leaves in a manner substantially identical to that shown in Fig. 10 but in which the several layers or leaves of each component are formed of metal having the same coefficients of expansion. In such a construction the operation would be substantially the same as that described in connection with Fig. 3.

In addition to the types of springs herein described it is also within the concept of the present invention to provide springs wherein each component comprises one, two or a multiplicity of arms having their free extremities in engagement for wrapping contact with the corresponding portions of a similarly constructed component. In such constructions there may be three or more arms for each component of the spring. Said arms may be formed integral with each other and two components may, as a matter of fact, be integrally formed of each other. Alternatively, a plurality of arms may be embedded in rigid supports in a manner similar to that illustrated in Figs. 4 and 5 of the drawings.

From the foregoing description it will be realized that the present invention comprises a plurality of spring constructions which are useful for opposing the forces of attraction of electromagnets since their resistance increases with a displacement of a portion thereof in accordance with a law similar to that in which magnetic attraction increases with the air gap between the armature and the pole pieces.

While the spring arms as illustrated in the drawings appear to be of uniform cross section throughout their lengths, it is within the concept of this invention to form said arms of modified cross sections.

Having described my invention, I claim:

1. An electric regulator comprising a carbon pile, an electromagnet having two relatively movable parts displaceable by electromagnetic action, to urge the relatively movable parts apart against the action of the magnet, two leaf spring components each formed of inclined arms, said components being positioned with the inner angles between said arms facing each other and the ends of the arms of one in contact with the ends of the arms of the other, means on one part of the electromagnet engaging one spring component between its arm ends, and means on the other part of the electromagnet engaging the other spring component between its arm ends, said spring components being operative to urge the said movable parts apart against the action of the magnet.

2. An electric regulator having a carbon pile, an electromagnet mechanically attached to one end of said pile, an armature for said electromagnet, a spring comprising two components each formed of inclined arms having their concave surfaces facing each other and the corresponding arm ends engaging each other tangentially, said spring being compressed between said electromagnet and said armature, and means connecting said armature and spring together and to the other end of said pile, so that movement of the armature towards the magnet wraps the arms of one spring component upon those of the other and the pile is subjected to the difference between the magnet pull and the spring pressure.

3. An electric regulator having a carbon pile, an electromagnet mechanically attached to one end of said pile, an armature for said electromagnet, a leaf spring of at least two arms abutting at one end upon each other tangentially to form a V, the other ends of said arms being compressed be-

tween said electromagnet and said armature, and means connecting said armature to the other end of said pile, so that movement of the armature towards the magnet wraps the abutting spring ends one upon the other and the pile is subjected to the difference between the magnet pull and spring pressure.

4. In a control apparatus, comprising an abutment device having mutually inclined surfaces, a resilient beam bridging said surfaces, an electromagnet having pole pieces, an armature, said pole pieces and armature constituting two relatively movable members, one of said members being connected to said abutment and the other member being connected to the mid point of the resilient beam, said members operating upon energization of the electromagnet to force the mid point of the beam further towards the angle between the surfaces of the abutment, causing the end portions of the beam progressively to contact the mutually inclined surfaces, progressively reducing the effective length of the beam bridged between them and progressively increasing the resistance to displacement by the electromagnet, and a carbon pile electric resistance having a movable member for varying the compression of the pile actuated by the relative displacement of said electromagnet pole pieces and armature; the construction that the abutment surface with mutually inclined surfaces is resilient.

5. In a control apparatus, comprising an abutment device having mutually inclined surfaces, a resilient beam bridging said surfaces, an electromagnet having pole pieces, an armature, said pole pieces and armature constituting two relatively movable members, one of said members being connected to said abutment and the other member being connected to the mid point of the resilient beam, said members operating upon energization of the electromagnet to force the mid point of the beam further towards the angle between the surfaces of the abutment, causing the end portions of the beam progressively to contact the mutually inclined surfaces, progressively reducing the effective length of the beam bridged between them and progressively increasing the resistance to displacement by the electromagnet, and a carbon pile electric resistance having a movable member for varying the compression of the pile actuated by the relative displacement of said electromagnet pole pieces and armature, the construction that the said beam and abutment are both in the form of springs.

6. An electric regulator having an electromagnet having a core and an armature, windings on said core and armature, a carbon pile having a fixed element retained in position by the core and a movable element displaceable by the armature, to relieve pressure on the carbon pile upon attraction of the armature to said core, and a spring opposing movement of the armature by electromagnetic force and compressing the carbon pile, characterized by said spring comprising two components each formed of inclined arms, said components having the inner angles between said arms facing each other and the corresponding arm ends engaging each other, whereby upon urging the components together intermediate their ends, greater portions of one component will contact greater portions of the other adjacent their ends to shorten the span of the components between their contacting portions and thereby increase resistance to further flexure.

7. An electric regulator comprising an electromagnet having a U-shaped core, an armature for

bridging the ends of said core, means including a rounded projection on said core for positioning one end of the armature relative to one end of the core for movement about said core end as a fulcrum, means for positioning the other end of the armature relative to the other end of the core for movement toward and away from said other end of the core, a carbon pile having a fixed pile compressing element associated with said core and a movable pile compressing element associated with said movable end of the armature, and spring means for opposing movement of the movable end of the armature toward said core and the movable end of the armature.

8. An electric regulator comprising an electromagnet having a U-shaped core, an armature for bridging the ends of said core, fulcrum means whereby one end of the armature can turn about one end of the core, the other end of the armature having an opening therethrough, a screw carried by the core and projecting through the opening in the armature, a carbon pile with two terminal discs between which the pile is compressible said pile being mounted on the part of said screw projecting through the opening and having one terminal disc fixed to the end of said screw and its other terminal disc movable by said armature, and spring means for opposing movement of the armature toward said core and for compressing of the carbon pile.

9. An electric regulator comprising an electromagnet having a U-shaped core, an armature for bridging the ends of said core, fulcrum means between one end of the armature and one end of the core, means for positioning the other end of the armature relative to the other end of the core for movement toward and away from said other end of the core, a carbon pile having a fixed pile

compressing element associated with said core and a movable pile compressing element associated with said movable end of the armature, and spring means for opposing movement of the movable end of the armature toward said core and for compressing of the carbon pile, said spring means comprising two components each formed of inclined arms having their concave surfaces facing each other and the corresponding arm ends engaging each other tangentially and wrapping upon each other.

10. An electric regulator comprising an electromagnet having a U-shaped core, an armature for bridging the ends of said core, fulcrum means between one end of the armature and one end of the core, the other end of the armature having an opening therethrough, a screw carried by the core and projecting through the opening in the armature, a carbon pile with two terminal discs between which the pile is compressible said pile being mounted on the part of said screw projecting through the opening and having one terminal disc fixed to the end of said screw and its other terminal disc movable by said armature, and spring means for opposing movement of the movable end of the armature toward said core and for compressing of the carbon pile, said spring having two stressed components portions of which are wrapped upon each other.

11. An electric regulator according to claim 2 in which the two springs are joined together as a unit and one of them has an extension by which the unit is attached to the regulator.

12. An electric regulator according to claim 2 comprising also projections on said core and armature between which the two springs are lodged and an adjusting screw in one of said projections for varying the initial compression of the springs.

FREDERICK NEWTON.
